(57) **CLAIM**

(**) Term: **14 Years**

The ornamental design for an electric connector for memory card, as shown.

(21) Appl. No.: **29/165,500**

DESCRIPTION

(22) Filed: **Aug. 13, 2002**

FIG. 1 is a perspective view of the top, front and left side of an electric connector for memory card showing our new design;

(30) **Foreign Application Priority Data**

FIG. 2 is a perspective view of the bottom, rear and right side view thereof;

Feb. 15, 2002 (JP) 2002-003662

FIG. 3 is a front elevational view thereof;

(51) LOC (7) Cl. **14-02**

FIG. 4 is a top plan view thereof;

(52) U.S. Cl. **D14/433**; D13/147

FIG. 5 is a rear elevational view thereof;

(58) **Field of Search** D14/432, 433,

FIG. 6 is a bottom plan view thereof;

D14/434, 435; D13/146, 147; 439/159,
160, 607-610; 369/291, 292

FIG. 7 is a right side elevational view thereof; and,

(56) **References Cited**

FIG. 8 is a left side elevational view thereof.
